(57) **CLAIM**

We claim the ornamental design for a utensil case, substantially as shown and described.

DESCRIPTION

FIG. 1 is a perspective view of a utensil case in accordance with the present design in an open position.

FIG. 2 is a top plan view of the utensil case in the open position.

FIG. 3 is a bottom plan view of the utensil case in the open position.

FIG. 4 is a right side elevational view of the utensil case in the open position.

FIG. 5 is a left side elevational view of the utensil case in the open position.

FIG. 6 is an upper end elevational view of the utensil case in the open position.

FIG. 7 is a lower end elevational view of the utensil case in the open position.

FIG. 8 is another perspective view of the utensil case in the open position showing utensils stored therein, it being understood that the broken lines are for illustrative purposes only and form no part of the claimed design.

FIG. 9 is another top plan view of the utensil case in the open position showing utensils stored therein.

FIG. 10 is a right side elevational view of the utensil case in the open position showing utensils stored therein.

FIG. 11 is a perspective top view of the utensil case in a closed position.

FIG. 12 is a perspective bottom view of the utensil case in a closed position.

FIG. 13 is a top plan view of the utensil case in the closed position.

FIG. 14 is a bottom plan view of the utensil case in the closed position.

FIG. 15 is a right side elevational view of the utensil case in the closed position.

FIG. 16 is a left side elevational view of the utensil case in the closed position.

FIG. 17 is an upper end elevational view of the utensil case in the closed position; and,

FIG. 18 is a lower end elevational view of the utensil case in the closed position.

The broken lines are shown for illustrative purposes only and form no part of the claimed design.
